BIRDHOUSE

Morris F. Booth, Alden, Mich.

Application July 19, 1938, Serial No. 220,069

8 Claims. (Cl. 119—23)

This invention relates to birdhouses and particularly to that type of birdhouse which is made up of detachably connected pieces whereby the house may be assembled or disassembled with ease.

An object of the present invention is to provide a birdhouse which may be easily taken apart for cleaning or for shipping.

Another object of the invention has to do with a novel construction arrangement in which a birdhouse may be built up piece by piece and firmly fastened together to provide a solid structure. An additional object has to do with that feature of the construction which permits the birdhouse to be bodily removed from its supporting bottom member so that the birdhouse may be readily cleaned.

A further object of the invention relates to a novel construction for ventilating a plurality of compartments in a birdhouse without exposing the same to the weather; and to a novel roof construction which does away with the necessity of forming a slanting roof.

A still further feature of the invention has to do with the novel roof construction which permits water to be retained on the top thereof to cool the house and serve as a bird bath.

Other objects and features of the invention have to do with details of construction and assembly and with be brought out in the following description and claims.

In the drawings:

Fig. 1 is a perspective view of the assembled house.

Fig. 2 is a sectional side view taken on the lines 2—2 of Fig. 1.

Fig. 3 is a sectional plan view taken on the lines 3—3 of Fig. 1.

Fig. 4 is a perspective view illustrating certain of the details of the construction at the corner posts.

Fig. 5 is a section in the corner post taken on the lines 5—5 of Fig. 4.

Fig. 6 illustrates an end portion of a roof piece for the birdhouse.

Figs. 7 and 8 are detail sections taken on the lines 7—7 and 8—8 respectively, of Fig. 3.

Fig. 9 shows an end of one of the ledge members of the birdhouse.

Referring to Fig. 1, the base of the multiple-compartment birdhouse is designated generally as 10 and the main elements of the structure consist of corner posts 11, lower and upper side members 12 and 12a and 13 and 13a, lower and

upper ledges 14 and 15, a roof 16, a roof covering 17 and roof retaining bars 18 and 19.

In Fig. 4, certain of the details of construction are illustrated. The corner post 11 is provided with vertical slots 20 and 21 on adjacent inside faces thereof. The ends of the lower side members 12a and 13a are fitted into these slots 20 and 21, as shown. The side members 12a and 13a are also provided with grooves 22 and 23, respectively, at different levels from the floor 10. These grooves 22 and 23 may either be cut in from the vertical surfaces of the side members 12a and 13a as shown in Fig. 4, or they may be cut in the edges of the members, if such is desired. (See grooves 24, Fig. 2.) Positioned directly above the lower side members 12a and 13a are the lower sides 12 and 13 which also have their ends retained in slots 20 and 21, respectively, of the corner posts 11. Directly above the side members 12 and 13 are found the ledges 14 and 15. These ledges have notches cut therein to receive the corner posts and they are mitered as at 25 so that a neat joint is formed. If desired the mitered surfaces may be slotted and a feather piece 26 inserted therein to hold the ledges in line (Fig. 1).

The details of the end formation of the ledges 14 and 15 are shown particularly in Fig. 9 where it will be seen that a notch 32 in the ledge provides a projecting portion 33 to be received by the slots 20 or 21. The top surface of the member 14, as shown in Fig. 9, is actually the lower surface in the assembly and is provided with spaced grooves 34, one of which is shown in Fig. 9. The function of these grooves will later be referred to.

Passing through the grooves 22 and 23 in the slides 12a and 13a are rods 27 and 28 which pass from one corner post to another to hold the parts assembled. In Fig. 5 these rods are shown each provided with a threaded end 29 which is received in a threaded cap 30 having an enlarged head 31. The other ends of the rods 27 and 28 may be provided simply with an enlarged end.

The second story of the birdhouse is built up in substantially the same manner as the first story described in connection with Fig. 4. Above the ledges 14 and 15, the upper side members 12a and 13a are placed and, in turn, upper sides 12 and 13 with ledges 14 and 15 are superimposed, all joining the corner posts 11. Each of the sides 12 is provided with bird openings 35 and each of the sides 13 is provided with a bird opening 36. Passing through the upper side members 12 and 13 are grooves 24, see Fig. 2, through which rods

37 and 38 project between the corner posts 11 as previously described in connection with rods 27 and 28. When the sides have thus been built up to the upper ledges 14 and 15, Fig. 1, partitions to be supported by the bottom of the house, may then be placed in the birdhouse. These partitions are provided for each story of the birdhouse and consist of longitudinal members 39 and cross members 40 which are interlocked to provide the nine compartments shown, for example, in Fig. 3. Between the upper and lower partitions a floor is located formed of pieces 41 and 42 which are supported by the lower partition members and notched at the corners to receive the corner posts 11.

The top of the birdhouse, which is generally indicated at 16, is composed of flat pieces 43 extending between the top ledge members 14. The end pieces 43 are notched at the corners to receive the corner posts 11. Covering the top pieces 43 is a waterproof asphalt or tar paper 17 which is held flat against the top 43 by cross bars 18 and 19, the ends of which are fitted into the slots 20 and 21 of the corner posts. These retaining bars 18 and 19 are pressed tightly down against the waterproof covering 17 which projects past the roof pieces 43 to cover portions of the top ledge members 14 and 15. Plugs 44 may be used to fill the top of the slots 20 and 21 and to hold the retaining bars 18 and 19 in position if such is necessary.

Each of the eight outside compartments on each floor is open to one entrance aperture 35 or 36 and each is ventilated by the slots 34 in the ledges 14 and 15. Each ledge 14 and 15 is provided with three slots 34 spaced to register with a compartment, Fig. 2. The corner compartments are thus open to two of the slots while the middle compartments are open to one.

The bottom of the birdhouse which has been generally designated as 10, preferably is formed of two boards 45 and 46 which are joined at an adjacent edge by a dovetail joint shown in Fig. 7. The ends of the boards 45 and 46 are bordered by strips 47 which are dovetailed into slots 48 in said ends. Passing through the slots 48 are rods 49 serving to hold the bottom portions together, Fig. 8. Studs 50 are doweled into the bottom at each corner thereof, Fig. 3, directly adjacent a corner post and sides 12a whereby the entire birdhouse assembly is fixed on the bottom against a relative sliding movement. Hooks 51 serve to fasten the bottom to the superstructure, Fig. 1.

When the birdhouse is to be cleaned or painted, the hooks 51 are released and the entire building may be removed from the bottom 10 simply by lifting the same away from the studs 50. Since the partitions of both stories of the house are supported on the bottom, they will readily slip from the shell of the house and may be cleaned conveniently. In this way the roof assembly may be made a permanent one.

It will be seen, then, that the birdhouse is so formed that it is completely knock-down to permit a convenient shipping package to be made of the parts. Additional stories may be added to the assembly simply by providing longer corner posts and building up the structure with parts identical with those described. Similarly, added length or width may be given to the assembly by utilizing the corner posts as shown and providing longer sides.

On the top of the structure the retaining bars in conjunction with the corner posts form a

tight wall surrounding and raised from the roof covering 17. In this way a reservoir is formed which will catch rainfall. A bird bath is thus formed on the top of the house and also the evaporation of water from said reservoir will cool the upper stories of the house considerably.

What I claim is:

1. A multiple-compartment birdhouse comprising a bottom piece, corner posts supported thereby and provided with vertical slots, side members for said birdhouse having ends to be detachably received by said slots, partition members arranged within the said side members to form a plurality of compartments in cooperation with said side members, apertures formed in said side members, each leading to a compartment, and a roof over said compartments comprising one or more cross pieces supported by said side members, a relatively flat waterproof sheet covering said cross pieces and extending between said posts, and restraining bars detachably positioned between said posts to hold the covering in position.

2. A multiple-compartment birdhouse comprising a bottom piece, corner posts supported thereby and provided with vertical slots, side walls for said birdhouse having ends to be received by said slots, partition members arranged within the said side walls to form a plurality of compartments in cooperation with said side walls, apertures formed in said walls, each leading to a compartment, a roof over said compartments comprising one or more cross pieces supported by said side walls and a waterproof sheet covering said cross pieces and extending between said posts, and retaining bars between said corner posts for holding said sheet and said roof cross pieces in position.

3. A multiple-compartment birdhouse comprising a bottom piece, corner posts supported thereby and provided with vertical slots, side walls for said birdhouse having ends to be received by said slots, partition members arranged within the said side walls to form a plurality of compartments in cooperation with said side walls, apertures formed in said walls, each leading to a compartment, a roof over said compartments comprising one or more cross pieces supported by said side walls and a waterproof sheet covering said cross pieces and extending between said posts, and retaining bars between said corner posts for holding said sheet and said roof cross pieces in position and arranged to fit snugly against said sheet and said posts, to form a reservoir to retain rainfall which may serve as a bird bath and cooling medium for said house.

4. A multiple-compartment birdhouse comprising a bottom piece, corner posts supported thereby and provided with vertical slots, side walls for said birdhouse having ends to be received by said slots, partition members arranged within said side walls to form a plurality of compartments at different levels in cooperation with said side walls, apertures formed in horizontal rows in said side walls, each leading to a compartment, and outwardly projecting ledges on said side walls over each row of apertures, said ledges having projecting portions for engaging said slots in said corner posts, and a roof over said compartments.

5. A multiple-compartment birdhouse comprising a bottom piece, corner posts supported thereby and provided with vertical slots, side walls for said birdhouse having ends to be received by said slots, partition members arranged within said side walls to form a plurality of compartments at different levels in cooperation with said side walls,

apertures formed in horizontal rows in said side walls, each leading to a compartment, and outwardly projecting ledges on said side walls over each row of apertures, said ledges having projecting portions for engaging said slots in said corner posts, and a roof over said compartments, said ledges having openings leading to each of said compartments from the outside of said house to afford ventilation of said compartments.

6. A multiple-compartment birdhouse comprising a bottom piece, corner posts supported thereby and provided with vertical slots, side walls for said birdhouse having ends to be received by said slots, partition members arranged within said side walls to form a plurality of compartments at different levels in cooperation with said side walls, apertures formed in horizontal rows in said side walls, each leading to a compartment, and outwardly projecting ledges on said side walls over each row of apertures, said ledges having projecting portions for engaging said slots in said corner posts, and a roof over said compartments, said ledges having openings in the bottom surfaces thereof leading to each of said compartments from the outside of said house to afford ventilation of said compartments.

7. A multiple-compartment birdhouse comprising a bottom piece, corner posts supported thereby and provided with vertical slots, side members for said birdhouse having ends to be received by said slots, partition members arranged within said side members to form a plurality of compartments at different levels in cooperation with said

side members, apertures formed in horizontal rows in said side members, each leading to a compartment, and outwardly projecting ledges on said side members over each row of apertures, said ledges having projecting portions for engaging said slots, and retaining rods between said corner posts for holding said posts, sides, and ledges in assembled relation whereby the birdhouse assembly may be removed bodily from said bottom

10 piece to permit cleaning thereof.

8. A multiple-compartment birdhouse comprising a bottom piece, corner posts supported thereby and provided with vertical slots, side walls for said birdhouse having ends to be received by said slots, partition members arranged within said side walls to form a plurality of compartments at different levels in cooperation with said side walls, apertures formed in rows in said side walls, each leading to a compartment, and outwardly projecting horizontal ledges on said side walls over each row of apertures, said ledges having projecting portions for engaging said slots, retaining rods between said corner posts for holding said posts, sides, and ledges in assembled relation, a roof over said compartments comprising one or more cross pieces supported by said side walls and a waterproof sheet of material covering said cross pieces and extending between said posts, and retaining bars having ends in said slots and adapted to hold down said sheet material and said roof cross pieces.

MORRIS F. BOOTH.
